UNITED STATES PATENT OFFICE.

BARTON R. SHOVER, OF CHICAGO, ILLINOIS, AND ARTHUR C. EASTWOOD, OF CLEVELAND, OHIO.

CONTROLLING SYSTEM FOR HOISTS.

No. 885,961.

Specification of Letters Patent.

Patented April 28, 1908.

Application filed June 20, 1907. Serial No. 379,885.

To all whom it may concern:

Be it known that we, BARTON R. SHOVER, a citizen of the United States, residing at Chicago, in the county of Cook and State of Illinois, and ARTHUR C. EASTWOOD, a citizen of the United States, residing at Cleveland, in the county of Cuyahoga and State of Ohio, have invented or discovered new and useful Improvements in Controlling Systems for Hoists, of which the following is a specification.

Our invention relates to new and valuable improvements in controlling systems for hoists and is specifically applicable to that class of hoists generally known as skip hoists, though it may also be advantageously applied to hoists of other forms. Skip hoists are commonly used in connection with blast furnaces for elevating the ore, limestone, coke, or other burden for the furnace from the ground or storage bins to the top of the furnace. In general, such hoists consist of an inclined runway extending from the ground to the furnace top and provided with rails for accommodating a skip-car or bucket, which is drawn up the runway by means of cables actuated by a suitable winding engine. Usually and preferably two skip cars are employed so connected to the drums of the winding engine that one car is ascending the incline while the other is descending, thus forming a balanced hoist.

It is desirable that the skip cars or buckets be arranged to discharge their contents automatically into the bell or hopper at the furnace top. It is further desirable that the skip car be brought to rest automatically at the proper point when it has discharged its contents, for the reason that not only is labor dispensed with, but additional safety is insured, providing, of course, that the automatic system of control is so designed and constructed as to be safe and reliable in service.

In the past it has been deemed expedient to gradually slow down the speed of travel of the skip-car as the car approached the limit of travel, this being accomplished by gradually reducing the power supplied to the winding engine. The purpose of this slowing down of the car has been to bring it as nearly as possible to a constant slow speed regardless of load before applying a retarding or braking force to the winding engine with the hope that in this way a more accurate stop may be secured with the skip-car always at the same point of travel. To accomplish

this result it has been customary (when an electric motor has been employed to drive the winding engine) to gradually cut resistance into the armature circuit of the motor to reduce its speed. If the same amount of resistance is inserted in the armature circuit of the motor irrespective of the load, necessarily the same reduction in speed will not be secured with varying loads. Thus, for instance, in the case of a direct current shunt wound motor operating on a circuit at 250 volts, if a resistance of $\frac{1}{2}$ ohm be inserted in the armature circuit with a load equivalent to 400 amperes, the voltage applied to the motor armature will be reduced to 50 volts. If the same resistance be inserted at a load equivalent to 100 amperes the voltage will only be reduced to 200 volts, so that necessarily there will be a wide variation in speed between these voltages. An endeavor to remedy this difficulty has introduced great complication in the controlling apparatus, since with this procedure it becomes necessary to automatically vary the amount of resistance inserted in the armature circuit in accordance with the load or else an automatically graduated retarding or braking force must be provided which will properly interpret variations in speed. By our invention we eliminate this complication and thus render the system of control much simpler and more reliable.

In carrying out our invention, we preferably employ a compound wound motor. The series field winding is employed only in starting and as soon as the load is accelerated the series winding is short circuited and the motor operated as a shunt wound motor. Such a motor will operate at a substantially constant speed within its range of loading regardless of the load. Therefore, whether the skip-car be loaded with coke or with ore (which has nearly four times the weight of coke) the skip-car will travel up the incline at the same speed and likewise the armature of the motor and the driven parts of the winding engine will maintain a given speed.

We do not attempt to slow down the motor by reducing the power supplied to it as the limit of travel is approached, but at a given point entirely cut off the supply of power. Since the skip-car invariably travels at the same speed irrespective of its load, gravity will retard and stop the upward bound skip-car in the same distance invari-

ably, and since the other parts are always moving at the same speed when the power is cut off, the amount of energy to be dissipated in bringing them to rest is always the same. We automatically cut off the power from the winding engine at a considerable distance from the limit of travel of the upward bound skip-car, this distance being dictated by the mass and velocity of the moving parts. In this way a large part of the energy stored in the moving parts is utilized in completing the travel of the skip-car with its load against gravity. Our invention, therefore, provides a system which is highly efficient and at the same time largely reduces the wear and tear on the hoisting mechanism since, when the final stop is made, a large part of the energy in the moving parts has already been utilized in performing useful work, so that very little remains to be absorbed in bringing the moving parts completely to rest. Our invention also provides means for effecting the final stop promptly, but in a manner which precludes injurious shock to the hoisting mechanism and cables.

Referring to the accompanying drawings, Figure 1 is a side elevation of a blast furnace showing the inclined runway with skip-cars thereon. Fig. 2 is a plan of the runway and engine. Fig. 3 is a side elevation of our preferred form of automatic cut-off device. Fig. 4 is a section on the line 4—4 on Fig. 3. Fig. 5 is a side elevation of the switches carried by the base p^{13} , the switches being reversed from the position of the corresponding switches in Fig. 3. Fig. 6 is a diagram of electrical connections.

In Fig. 1, F is a blast furnace provided with an inclined runway f^1 , upon which the skip-cars f^2 and f^3 travel.

f^6 is a machinery house in which are located motor-driven winding drums f^4 and f^5 , which, through suitable cables propel the skip-cars on the runway.

As indicated in Fig. 2, one of the cars invariably travels up the incline while the other is traveling down, thus forming a hoist in which the weight of one skip car balances that of the other. At the upper end of the inclined runway, it will be seen that the rails f^8 which accommodate the forward trucks of the skip-car deflect downward while the rails f^7 which accommodate the rear wheels of the car are elevated, thus causing the skip-car to assume the position indicated when the limit of travel is reached in which position the skip-car automatically discharges its load.

f^9 indicates a storage bin from which the skip-cars are alternately filled through hoppers or chutes. The arrangement of the hoisting engine is more clearly shown in Fig. 2 in which M is a driving motor. This motor drives through suitable gearing the drums f^4 and f^5 . One end of the drum shaft is provided with an extended screw c^1 , which serves

to actuate a cross head C, which is provided with a suitable nut in engagement with the screw. These parts are more clearly shown in Figs. 3 and 4 and form the actuating means for automatically cutting off the power and subsequently stopping the hoist at a predetermined point.

The cross head C is guided by a guide frame H and through the engagement of the nut c^2 with the screw c^1 the cross head is driven back or forward along the guide-way in accordance with the rotation of the screw c^1 . Since this screw is directly attached to the shaft of the hoisting drums, the cross head C will always move in synchronism with the hoisting drum so that definite points in the travel of the cross head represent definite travels of the hoisting cable. The cross head C is provided, on either side, with T-shaped slots c^7 , which accommodate the heads of bolts c^8 , which in turn serve to adjustably clamp in place suitable actuating cams c^3 , c^4 , c^5 , c^6 . These cams are arranged in pairs at each end of the cross head, one member of each pair being set somewhat ahead of the other for reasons which will be later explained. Each of the cams co-operates with a cam roller p^2 carried at the extremity of its respective lever p^1 , pivoted to swing at p^{14} .

When a cam comes into engagement with the corresponding cam roller the lever p^1 actuates a corresponding cross head p^4 in such manner as to multiply the motion of the cam, the lever p^1 being pivoted near its upper end and in engagement with the cross head p^4 near its lower end. The cross head p^4 moves upon a suitable guide p^{12} , mounted upon a slate or other insulating base, p^{13} . The cross head p^4 carries two brushes, p^5 , p^6 , the brush p^5 being adapted to connect together the strips p^7 , p^8 , and the brush p^6 being adapted to electrically connect the strips p^9 , p^{10} . Each of the outermost strips are provided with short sections or tips p^{14} by suitably connecting which the electrical length of the corresponding strip may be adjusted. When, for instance, the brush p^6 passes to the left beyond the last one of these adjustable tips p^{14} , which is in circuit, the connection between strips p^9 , p^{10} is opened. When the direction of motion of the cross head C is reversed by reversing the direction of rotation of the hoisting drum, the lever p^1 is returned to the vertical position by the spring p^{11} .

Fig. 6 shows the various electrical connections in our invention as used in connection with a compound wound, direct current motor. While we find such a motor well adapted to the purpose, it is to be understood that our invention is not limited to the use of such a motor as certain broad features of our invention are equally applicable to hoists driven with other forms of motors, or with steam engines or other prime movers.

In Fig. 6, A is the armature of the driving motor. F is the series field winding, and f , the shunt field winding of the motor. b is the winding of the releasing magnet of the 5 friction brake B, this brake being of well known construction wherein the brake is released when the magnet is energized and is applied by means of a weight or spring b' when the magnet is deenergized. It is to be noted 10 that the magnet winding b is connected in parallel with the switch coil S^1 . U, U', D, D' are reversing switches which close in pairs to give one or the other direction of rotation to the armature A in the well known way, the 15 switches U, U' giving one direction of rotation, and the switches D, D', the reverse direction. r^1 , r^2 , r^3 are sections of starting resistance which are controlled by the magnetically operated switches R¹, R², R³ in automatically starting the motor. F¹ is a magnetically operated switch, which, when closed 20 short circuits the series field winding F and allows the motor to operate as a simple shunt wound motor. A series relay or throttle O 25 automatically governs the successive closure of the switches R¹, R², R³ and F¹ in the manner clearly described in Arthur C. Eastwood's application for United States Patent, Serial No. 352,408. We do not, however, confine 30 ourselves to this precise system of automatically cutting out the starting resistance, but we consider this a preferable arrangement. r^4 is a resistance in shunt with the winding of the series relay O and may be used for adjusting 35 the proportion of current which flows through the winding of the relay, thereby adjusting the amount of current to be taken in accelerating the motor. S is a magnetically operated switch which controls a circuit 40 through the armature of the motor, the contacts of the switch S, and the resistance r^5 . The winding of the switch S is connected directly across the terminals of the armature so that it tends constantly to close while the 45 armature is running. It is, however, normally prevented from closing by the mechanical interlocking levers l^3 and l^4 which are so arranged that switch S cannot close when either of the neighboring switches U' or D' is 50 closed. S¹ is a second dynamic braking switch which is normally closed by a spring S² and which is opened when the winding of the switch is energized. This switch is also mechanically interlocked by means of the levers 55 l^1 and l^2 with its neighboring switches U, D so that it cannot close when either of the said switches is closed. The switch S¹ controls a circuit through the armature of the motor A, and the winding I, which is of low ohmic 60 resistance, but of high inductance. The winding I is preferably inclosed in a complete, or practically complete, magnetic circuit of heavy section. We make use of this construction to provide what might be termed a 65 "magnetic cushion" which is made use of in bringing the motor to rest in minimum time yet without severe shock when the limit of travel is reached. The switch S¹ closes at a point very close to the limit of travel. When it closes, the armature A tends to generate 70 current through the closed circuit in which it is included by the closure of the switch S¹. The highly inductive nature of the winding I, although it has a low ohmic resistance, does not permit an excessive current to flow, since 75 the building up of the magnetism in the magnetic circuit which surrounds the winding I chokes back the flow of current due to the inductive action of the increasing magnetic field. As the magnetism builds up this choking 80 action is reduced but the speed of the armature has also been reduced through the work which it has performed in forcing current through the closed circuit. Consequently, as the choking action of the inductive winding I is reduced, the voltage available 85 for forcing current through the closed circuit is also reduced. Excessive rush of current is, therefore, prevented when the dynamic braking action is first instituted and 90 by this construction such a low ohmic resistance may be made use of in the winding I that the braking action will still remain very powerful even when the armature A has been brought down to a very slow speed. 95

K is the operating controller which is shown with the operating lever in the vertical, or off-position. This controller is operated manually in one direction or the other by the operator to start the hoist either up or 100 down. Merely the throwing of this switch is required on the part of the operator, as the starting resistance is automatically cut out and when the limit of travel is reached the hoist is automatically stopped. 105

C represent the switches actuated by the automatic stop mechanism. The switches D+, D- control the circuits of the operating electro-magnets of reversing switches D, D'. Switches U+, - U control the circuits of the 110 operating electro-magnets of switches U, U'. Switches S¹+, S¹- control the operating circuit of the dynamic braking switch S¹. In the drawing switches D+, D-, S¹+, S¹-, are indicated as open, in which position the 115 hoist will have reached its upward limit of travel and have been automatically stopped. If the operating lever of the controller K be now moved to the right so that the contact brush l^{14} connects the contact rings k^1 , k^2 , k^3 120 and brush l^{13} connects the rings k^4 , k^5 , k^6 , the control circuits will be as follows: from the positive main to the contact ring k^3 , to the contact ring k^2 , thence through the switch S¹+, the winding of the dynamic braking 125 switch S¹, the switch S¹-, the contact ring k^5 , brush l^{13} to the negative main. This causes switch S¹ to open. The coil b of the brake being in parallel with the winding of switch S¹ is also excited and the brake conse- 130

quently released. Current also flows from the positive main to the contact ring k^3 , brush k^{14} , ring k^1 , switch $U+$ through the windings of the reversing switches U , U^1 in parallel, thence through switch $U-$, the contact ring k^4 , brush k^{13} and ring k^6 to the negative main. This causes the reversing switches U , U^1 to close. The main circuit through the motor is then established as follows: from the positive main, through the switch U , the armature A , the switch U^1 , the sections of resistance r^1 , r^2 , r^3 the current then dividing, a portion passing through the resistance r^4 and the remainder through the winding of the 15 overload relay O , this current re-uniting and flowing through the series field F to the negative main.

It is to be noted that the shunt field winding of the motor f is constantly connected across the supply mains. The motor should, therefore, start under the influence of both its shunt and series field, with the brake B released. As the motor speeds up the series relay O will permit the switches R^1 , R^2 , R^3 , 25 and F^1 to consecutively close, thereby short circuiting the sections of resistance r^1 , r^2 , r^3 and the series field winding F . As the armature speeds up the winding of the switch S , which as has been previously mentioned is 30 connected directly across the terminals of the armature, is energized and tends to cause the switch S to close. It is, however, prevented from closing by the interlocking lever l^3 which will not permit switch S to close while switch U^1 is closed. The switch S , however, tends to close and all of its parts are under a strain in what may be called an endeavor to close.

When the limit of upward travel is approached, the cam c^5 in Fig. 3 comes into contact with the cam roller p^2 of switches $U+$, $U-$, thus automatically opening these switches, which in turn opens the circuit through the magnets of switches U , U^1 , thus 45 causing these switches to open, thereby cutting off the supply of power to the armature of the motor. Switch S closes concurrently with the opening of the switch U^1 with which it is interlocked. As previously stated, this 50 switch is under a strain in an endeavor to close so that an exceedingly brief period elapses between the opening of switch U^1 and the closing of switch S . The closure of switch S establishes a circuit including the 55 armature A and the resistance r^5 in which the armature immediately generates current due to its rotation under the influence of the shunt field winding f .

It is not intended that a material amount 60 of energy shall ordinarily be absorbed and dissipated in the resistance r^5 , it being the intention that the moving parts of the hoist should be slowed down by continuing to lift the upward bound skip-car with its load 65 against gravity. The amount of resistance

r^5 in circuit may be adjusted to meet conditions of operation. For instance, where the handling of material at very high speed is required there may not be sufficient time allowable for slowing down the hoisting mechanism purely through the action of gravity on the upward bound skip-car. In such cases a minimum amount of resistance r^5 will be used, thus rendering the dynamic braking action more intense. Where more 70 time is allowable the resistance r^5 may be increased or may be entirely dispensed with. When the moving parts have been sufficiently slowed down in this way the cam c^3 comes into contact with its coöperating cam roller p^2 , thus automatically opening switches S^1+ , S^1- . This opens the circuit of the magnetizing coil of switch S^1 and allows this switch to instantly close and at the same time opens the circuit of the brake magnet b , 80 thus causing the brake to be applied. This establishes a second dynamic braking circuit through the armature of the motor A , the switch S^1 and the inductive winding I . As previously described a powerful, though 85 magnetically cushioned, dynamic braking action is set up, which brings the armature of the motor to rest in a minimum period of time and, therefore, with a minimum travel of the load being hoisted. 90

As the load has traveled upward the cross head C , in moving to the left, has caused the cam c^4 to release the switches S^1+ , S^1- and the cam c^6 to release the switches $D+$, $D-$. Consequently, when the upward limit of 100 travel has been reached these switches are closed and the hoist may be started down by simply reversing the position of the operating lever of the controller K . In this case the reversing switches D , D^1 are energized in 105 place of the reversing switches U , U^1 . In other respects the cycle of operations is the same as that described above in connection with the reverse direction of motion.

It is to be noted that the final dynamic 110 braking switch S^1 is opened by a magnet and is closed by a spring. Therefore, in case the supply of current fails at an intermediate position of the hoist, this switch will instantly close thereby connecting the armature of the 115 motor in a dynamic braking circuit and bringing it to rest under the influence of the shunt field f which dies out slowly owing to the high self-induction of the field winding. At the same time the brake B is automatically 120 applied and serves to safely hold the load until the supply of current is again established at which time the motor will again automatically be started, will drive the load to the limit of travel and will then be automatically stopped. 125

We claim—

1. In a balanced skip-hoist, an inclined runway, a pair of skip-cars having travel thereon simultaneously in reverse directions, 130

a winding engine for propelling either of said skip-cars up said inclined runway, and automatic means for dumping each of said skip-cars when its upper limit of travel is reached, 5 said automatic dumping means deriving the energy required to dump either of said upwardly moving skip-cars from the energy due to the downward motion of the other skip-car and the energy due to the motion of the 10 parts of said winding engine.

2. In a hoisting mechanism, an inclined runway, a skip-car traveling thereon, a winding engine for propelling said skip-car up said inclined runway and automatic means for 15 dumping said skip-car at a predetermined point on said runway, said automatic dumping means deriving the energy required to dump said skip-car from the energy stored in the moving parts of said hoisting mechanism.

20 3. In a hoisting mechanism, an inclined runway, a skip-car traveling thereon, and means for causing the energy stored in the moving parts of said hoisting mechanism to dump said skip-car at a predetermined point 25 on said runway.

4. In a hoisting mechanism, an inclined runway, a skip-car traveling thereon, a winding engine for drawing said skip-car up said runway, means for automatically cutting off 30 the power from said winding engine when said skip-car reaches a predetermined point on said runway, and for causing the energy stored in the moving parts of said hoisting mechanism to automatically dump said skip- 35 car.

5. In a hoisting mechanism, an inclined runway, a skip-car, a motor driven hoisting engine for propelling said skip-car up said runway, and automatic means for cutting off 40 the supply of power from said motor before the limit of travel of said skip-car is reached and for causing energy due to the motion of the parts of said hoisting mechanism to be absorbed in completing the travel of said 45 skip-car against gravity.

6. In a system of control for hoists, a load to be hoisted against gravity, a hoisting engine for hoisting said load, automatic means for supplying power to said hoisting engine 50 to accelerate said load, automatic means for cutting off the power from said hoisting engine when the load has reached a predetermined point of travel and causing the moving parts of said hoisting engine to slow down 55 through giving up the energy due to their motion in continuing to hoist said load against gravity, and automatically acting means for absorbing the residue of said energy when a second predetermined point of travel 60 is reached.

7. In a system of control for hoists, a load to be hoisted against gravity, a hoisting engine for hoisting said load, automatic means for supplying power to said hoisting engine 65 to accelerate said load, automatic means for

cutting off the power from said hoisting engine when the load has reached a predetermined point of travel, thus causing the moving parts of said hoisting engine to slow down through giving up the energy due to their 70 motion in continuing to hoist said load against gravity, automatically acting means for absorbing the residue of said energy when a second predetermined point of travel is reached, and a holding brake automatically 75 applied when the moving parts have substantially come to rest.

8. In a hoist, the combination of a load to be hoisted, a hoisting engine, a brake for said hoisting engine, automatic means for cutting 80 off the supply of power from said engine when a predetermined point of travel is reached, and means for automatically applying said brake when a second further point of travel is reached. 85

9. In an electric hoist the combination of a load to be hoisted, a motor driven hoisting engine, a mechanically applied brake for said motor, automatic means for entirely cutting off the power from said motor before the 90 limit of upward travel is reached, and automatic means for causing said brake to be applied when the limit of travel is reached.

10. In an electric hoist the combination of a load to be hoisted, a motor driven hoisting 95 engine, an automatic controller for starting said motor, automatic means for entirely cutting off the supply of power to the armature of the motor before the limit of travel of said load is reached, without previously 100 slowing down the motor, a brake on said motor normally released when power is supplied to the armature of said motor, and automatic means for preventing the application of said brake after power has been cut off 105 from the armature of said motor till said armature has substantially come to rest.

11. The method of slowing down and stopping a motor-driven hoist at a predetermined point which consists in automatically 110 cutting off the supply of power from the armature of the motor when a given position of travel is reached, thereby permitting the moving parts to be slowed down by lifting the load against gravity and, at a second given 115 point of travel, automatically connecting the mechanical brake to the hoisting mechanism.
